DESIGN FOR A GAME APPARATUS

Frederick Alexander Drake, New York, N. Y.

Application March 29, 1935, Serial No. 56,119

Term of patent 14 years

To all whom it may concern:

Be it known that I, Frederick Alexander Drake, a citizen of the United States, residing in the county of Kings, city and State of New York, have invented a new, original, and ornamental Design for a Game Apparatus, of which the following is a specification, reference being had to the accompanying drawing, forming part thereof.

The single figure of the drawing is a perspective view of a game apparatus, showing my new design.

I claim:

The ornamental design for a game apparatus, as shown.

FREDERICK ALEXANDER DRAKE.
